UNITED STATES PATENT OFFICE.

JOHN ROSS, OF PHILADELPHIA, PENNSYLVANIA.

RIGGER'S TRUCK.

No. 893,658.

Specification of Letters Patent. Patented July 21, 1908.

Application filed January 8, 1908. Serial No. 409,763.

To all whom it may concern:

Be it known that I, JOHN ROSS, a citizen of the United States, and a resident of the city and county of Philadelphia, State of Pennsylvania, have invented an Improvement in Riggers' Trucks, of which the following is a specification:

My invention has reference to riggers' trucks, and consists of certain improvements which are fully set forth in the following specification, and shown in the accompanying drawings, which form a part thereof:

The object of my invention is to provide a form of riggers' truck which will permit of such adjustment of its several parts as will adapt it for use under varied conditions, and which, moreover, will give it capacity for manipulation that will enable the most difficult loads to be handled with facility, whether in close quarters or on the road.

My invention consists of an upper frame having a downwardly extended tubular portion, combined with a lower frame in which a central supporting wheel is journaled, said frame extending upward and concentric with the tubular portion of the upper frame.

My invention further consists of the foregoing structure when also provided with a screw-threaded connection between the tubular part of the upper frame and the lower frame, whereby the former may be adjusted upon the latter to different elevations.

My invention also comprehends details of construction which, together with the features above specified, will be better understood by reference to the drawings, in which:

Figure 1 is a sectional elevation of a rigger's truck embodying my invention; Fig. 2 is a sectional plan view of the same taken on line 2—2 of Fig. 1; Fig. 3 is a sectional view of a portion of Fig. 1 on line 3—3; Fig. 4 is a plan view of the riggers' truck; Fig. 5 is a sectional elevation of a modified form of my improved truck; Fig. 6 is a sectional plan view on line 6—6; Fig. 7 is an elevation of another modification of my invention; Fig. 8 is a sectional plan view of the same on line 8—8; Fig. 9 is a sectional elevation of still another modification of my invention, showing the employment of two supporting wheels instead of one; and Fig. 10 is an end view of an operating wrench.

A is the upper frame and is preferably cir-

cular and provided with a downwardly extending tubular portion B preferably screw-threaded upon its interior.

C is a part of the lower frame and is provided with a cylindrical base C' and a tubular upwardly extending part screw-threaded upon its exterior for adjustably engaging the tubular part B, as clearly shown in Fig. 1. D is the other part of the lower frame and is formed of a circular base plate D' provided with an upward cylindrical part fitting with in the part C, so as to be adjustable axially therein. The parts C and D constitute the lower frame of the truck, and if desired may be secured together as a unit by means of bolts M, which extend through notches e in the flanges C' and D'. There may be many more of such notches in the flanges C' than in the flange D', one or more being sufficient in the latter. By employing notches instead of holes, it is easier to remove the bolts when necessary, should the parts be jammed.

F is the central supporting wheel and is secured to a shaft E which is journaled at d' to the under part of the frame D. The end of the shaft E may be made square for the attachment of a wrench or operating le. er. The wheel F extends well up into the tubular space within the lower frame D so as to bring the top of the truck as a whole as low down as possible. The upper frame A B may be adjusted to any desired height above the wheel F by rotating it upon the lower frame by means of a wrench shown in Fig. 10. A top plate or turn table G may rest upon the upper frame A, and may be centered by means of a downwardly extending central lug g at the center. This top plate may have projections i to bite into the timber or other material I constituting the support or sill for the load. These timbers I may be sills or stringers arranged under the sides of a house, for example, and may be supported upon two or more of my improved trucks. Flexible chain dogs J may be employed for holding the timber I centrally upon the top plate, these dogs being hinged to the periphery of the plate upon opposite sides. The top plate G may be secured firmly to the upper frame A by means of bolts H which extend through slots G' in the top plate, and A' in the top frame, as more fully indicated in Figs. 1 and 4. In this manner, the top plate G and the upper frame A may be rigidly secured to

gether after proper adjustment has been made. When the vertical adjustment is being made, the bolts H must be removed, and the upper frame A B turned with the wrench 5 shown in Fig. 10, after which the bolts H are replaced.

In Fig. 5, the screw adjustment between the parts B and C is omitted, and consequently the parts A B C C' are merged into 10 a single frame A² in which the lower frame D is journaled in precisely the same manner as said lower frame is journaled in the frame C C'.

In the construction shown in Figs. 7 and 8, 15 the same general structure is followed, but in this case the axle of the roller or wheel instead of being journaled in fixed bearings on the bottom of the frame D is journaled in an extra frame D² which is supported from a 20 base D' of the frame D by means of bolts K and springs L, of which four sets may be employed. In this manner, the truck body is spring-supported on the central roller F.

In some cases where the conveyance of articles is required over long distances and where larger supporting wheels are necessary to sustain the greater load, the truck may be 25 formed as indicated in Fig. 9, in which there are two supporting wheels F' F' and a bearing structure arranged between them on the bottom of the lower frame D.

When the load is to be conveyed in a straight path, the bolts M are employed; but when the travel is to be on a curve or in an 30 irregular course, then the bolts M are removed and the part D D' is turned to change the axis of the roller to suit the direction of travel desired.

While I prefer the construction shown, the 40 details may be modified without departing from the spirit of the invention.

Having now described my invention, what I claim as new, and desire to secure by Letters Patent, is:—

45 1. In a riggers' truck, an upper frame for supporting the load, and a lower frame connected to the upper frame by a screw-threaded joint having a vertical axis and by which the upper frame may be vertically adjusted 50 upon the lower frame, combined with a central roller having an axle journaled in the lower frame.

2. In a riggers' truck, an upper frame for supporting the load, and a lower frame connected to the upper frame by a screw-threaded joint having a vertical axis and by which the upper frame may be vertically adjusted 55 upon the lower frame said lower frame being provided with a pivoted portion, combined 60 with a central roller having an axle journaled in the pivoted portion of the lower frame.

3. In a riggers' truck, an upper frame for supporting the load, and a lower frame connected to the upper frame by a screw-threaded joint having a vertical axis and by which 65

the upper frame may be vertically adjusted upon the lower frame said lower frame being provided with a pivoted portion, combined with a central roller having an axle journaled in the pivoted portion of the lower frame, 70 and means for securing the pivoted portion of the lower frame in various positions of circumferential adjustment.

4. In a riggers' truck, an upper frame for supporting the load, and a lower frame connected to the upper frame by a screw-threaded joint having a vertical axis and by which the upper frame may be vertically adjusted 75 upon the lower frame, combined with a central roller having an axle journaled in the lower frame, and a top plate pivoted to the upper frame upon which the load rests.

5. In a riggers' truck, an upper frame for supporting the load, and a lower frame connected to the upper frame by a screw-threaded joint having a vertical axis and by which the upper frame may be vertically adjusted 80 upon the lower frame, combined with a central roller having an axle journaled in the lower frame, a top plate pivoted to the upper frame upon which the load rests, and means on the top plate for holding the load 85 in position thereon.

6. In a riggers' truck, an upper frame for supporting the load, and a lower frame connected to the upper frame by a screw-threaded joint having a vertical axis and by which the upper frame may be vertically adjusted 90 upon the lower frame, combined with a central roller having an axle journaled in the lower frame, a top plate pivoted to the upper frame upon which the load rests, and detachable means for adjusting and holding the top plate in different positions of adjustment on the upper frame.

7. In a riggers' truck, upper and lower frames having tubular parts engaging each other to form a sleeved joint and by which the lower part is centralized upon the upper part, combined with a roller support for the lower part, and a shaft carrying the roller and journaled in the lower part and having one end extended beyond the frames for rotating the roller.

8. In a riggers' truck, an upper frame having a downwardly extending tubular part, combined with a lower frame extending upward within the tubular part and circumferentially adjustable therein and having a lower part connected by springs, and a rolling support having a shaft journaled upon the lower part of the lower frame whereby the upper frame and the load are spring supported.

9. In a riggers' truck, an upper frame having a downwardly extending tubular part, combined with a lower frame extending upward within the upper frame and made hollow in the center, combined with a roller extending partly upward into and shielded by 130

the lower frame, and an axle for the roller journaled to the lower frame and extending laterally therefrom.

10. In a riggers' truck, a turn - table, a lower frame, a roller journaled to the lower frame to support it, and means intermediate between the turn-table and lower frame for connecting said parts and adjusting the turn-table vertically relatively to the lower frame.

11. In a riggers' truck, a turn - table, a lower frame, a roller journaled to the lower frame to support it, and means intermediate of the turn-table and lower frame consisting of an upper frame pivoted to the turn-table and 15 screwed upon the lower frame for connecting said parts and adjusting the turn-table vertically relatively to the lower frame.

12. In a riggers' truck, the truck proper combined with a turn-table having projections upon which the load may rest, and dogs comprising chains connected at one end to the turn-table and having spikes at the other end.

13. In a riggers' truck, an upper frame having a downward tubular part, a lower frame hollow in the center and having an upward tubular part engaging the tubular part of the upper frame and forming a shouldered engagement therewith, and a roller extending 25 into the hollow center of the lower frame by a shaft which projects laterally beyond the lower frame for rotating the roller and journaled to the lower part of said lower frame.

14. In a riggers' truck, upper and lower frames having tubular parts engaging each 35 frames having tubular parts engaging each other to form a sleeved joint and by which the lower part is centralized upon the upper

part, combined with a roller support for the lower part whereby the two frames may be radially adjusted relatively to each other 40 without changing their vertical positions, means for locking the frames in their relative adjusted positions, and a shaft carrying the roller and journaled in the lower part and having one end extended beyond the frames 45 for rotating the roller.

15. In a riggers' truck, upper and lower frames having tubular parts engaging each other to form a sleeved joint and by which the lower part is centralized upon the upper 50 part, combined with a roller support for the lower part, a turn-table arranged upon the upper frame, means for securing the turn-table in fixed relation upon the upper frame when required, and a shaft carrying the roller 55 and journaled in the lower part and having one end extended beyond the frames for rotating the roller.

16. In a riggers' truck, the combination of an upper flanged tubular frame, a lower 60 flanged tubular frame having its tubular part sleeved with the tubular part of the upper frame, a supporting roller device, a shaft for the roller device journaled on the bottom part of the lower frame, and means for adjustably clamping the flanged part of the lower frame to the upper frame.

In testimony of which invention, I have hereunto set my hand.

JOHN ROSS.
